UNITED STATES PATENT OFFICE.

HERMANN WIEDERHOLD, OF FURSTENWALDE-ON-THE-SPREE, GERMANY, ASSIGNOR
TO THE FIRM N. V. NEDERLANDSCHE MIJNBOUW EN HANDEL MAATSCHAPPIJ,
OF AMSTERDAM, NETHERLANDS.

PROCESS OF MANUFACTURING CYANIDES.

No Drawing. Application filed November 18, 1926, Serial No. 149,284, and in Germany December 10, 1925.

My invention relates to improvements in the process of manufacturing cyanides.

In the manufacture of alkali metal or barium cyanides in which nitrogen is caused to act on mixtures of substances containing carbon and oxides or carbonates of the alkali metals and the barium at elevated temperature the binding of the nitrogen should be effected as rapidly and completely as possible. A rapid binding is obtained if the coal and the metal compound are intimately mixed, the coal has a high degree of activity, and the nitrogen has a ready access to the mixture. The object of the improvements is to provide a process by means of which products answering this condition are obtained and, accordingly, alkali metal and barium cyanides are rapidly and economically produced. With this object in view my invention consists in manufacturing the said products from substances capable of producing highly active coal and having the property of producing a granular product when heated in mixture with alkali metal and barium compounds. A suitable matter of this character is the humic acid.

Humic acid or alkali metal humates obtained from matter containing humic acid are mixed with a sufficient excess of alkali metal or barium oxides or carbonates, and the mixture is heated while continuously removing the gaseous products. Thus a granular highly active coke is produced which is rich in alkali metal or barium.

Preferably in a separate oven, or in a second chamber of the same oven, the said coke is subjected to the second step of the process, in which it is heated in the nitrogen current at a temperature of about 1000° C. or more. By reason of the porosity of the granular coke the nitrogen is rapidly absorbed, and the alkali metal or barium oxide is almost completely used up for producing cyanide.

To the initial substance suitable catalysts such for example as iron compounds may be admixed, and I have found that as compared to processes heretofore in use small amounts of the catalyst result in a considerable acceleration of the reaction and in an improved yield.

Free humic acid is found natural mainly in the form of the so called coal humus

which, by reason of its brown colour, is also used as an earth dyestuff known in the trade as brown of Cassel. In some cases the coal humus contains much earth. Therefore I prefer to treat the same with alkali metal carbonate, to separate the solution of alkali metal humate from the earth, and to obtain the alkali metal humate pure while removing the water in a suitable way.

In some cases I break up matter such as peat or certain kinds of brown coal containing much humic matter by alkali metal compounds or by pressure hydrolysis with steam, in which case free humic acid or alkali metal humates are produced from the humic substances which in my opinion are of the nature of anhydrides, the said humic acid or alkali metal humate being separated and subjected to the above process.

I have found that when heating the pure alkali metal humates, and more particularly those obtained from coal humus, a material is obtained the binding power of which is so high that a granular porous coke can be obtained even if to the humates other products containing carbon are added which when heated by themselves do not yield suitable coke. I have discovered that up to about 60% of the said matter can be added.

The alkali metal compound can be added to the initial materials in the form of concentrated waste lyes of the industry which are rich in alkali metal compounds, and even such lyes may be used which have organic matter admixed thereto. In lieu of soda or potash mixtures of lime with salts of the alkali metals can be used.

Example 1.—2.5 hektoliters of moist coal humus containing about 57% H₂O and about 80% of humic acid calculated from the dry matter are mixed within a mixing drum of a length of 3 meters with 1 hektoliter of sodium which is free of water. Thus alkali metal humate is formed while carbonic acid is developed. After 10 or 15 minutes the material is removed from the drum in the form of a dark brown or black glutinous and doughy material. The said material is heated within a rotary oven up to 550° C. After thus heating the matter about 30 or 40 minutes, a compact coke is obtained the particles of which have the size of peas or walnuts. which coke is subjected to the azo-

tizing process. Prior to coking matter containing carbon such as 2 hektoliters of sawdust may be admixed to the coal humus.

Example 2.—1000 kilograms of Rhenish 5 brown coal containing 50% H_2O are finely ground and boiled with 150 kilograms of sodium carbonate and water while stirring. Thereafter the suspension is allowed to settle, and the solution is decanted from the 10 sediment formed, whereupon the solution containing the alkali metal humate obtained by the process is thickened as far as necessary before heating the same. Thereafter the thickened matter containing about 250 15 kilograms of alkali metal humate is mixed with 20 kilograms of Fe_2O_3 , heated and azotized.

I claim:

1. The herein described process of manufacturing cyanides, which comprises heating 20 matter containing free humic acid in the presence of a compound of an alkali metal and heating the coke thus produced at a temperature of at least about 1000° C. while causing nitrogen to act on the same.

2. The herein described process of manufacturing cyanides, which comprises heating alkali metal humate, and heating the coke thus produced at a temperature of at least about 1000° C. while causing nitrogen to act 30 on the same.

3. The herein described process of manufacturing cyanides, which comprises heating matter containing humic acid in the presence of an alkali metal compound to produce 35 a granular coherent coke, and heating the said coke at a temperature of at least about 1000° C. while causing nitrogen to act on the same.

4. The herein described process of manufacturing cyanides, which comprises heating 40 a mixture of matter containing humic acid in the presence of an alkali metal compound and a suitable carbon carrier, and heating the coke thus produced at a temperature of 45 at least about 1000° C. while causing nitrogen to act on the same.

5. The herein described process of manufacturing cyanides, which comprises treating matter containing free humic acid in 50 the presence of water with a suitable alkali metal compound, separating the solution from the solid residue, thickening the solution, heating the thickened matter to produce a granular coke therefrom, and heating the coke thus produced at a temperature of at least about 1000° C. in the presence of nitrogen.

6. The herein described process of manu-

facturing cyanides, which comprises boiling 60 matter containing humic substances with a basic alkali metal compound, separating therefrom the solid matter, thickening the solution by evaporation, heating the product in the presence of an alkali metal compound to form a coke therefrom, and heating the coke thus produced at a temperature of at least about 1000° C. in the presence of nitrogen.

7. The herein described process of manufacturing cyanides, which comprises heating matter containing humic acid in the presence of alkali metal salts, and a suitable catalyst, and heating the mixture thus produced at a temperature of about 1000° C. 75 in the presence of nitrogen.

8. The herein described process of manufacturing cyanides, which comprises heating matter containing humic acid in the presence of an alkali metal compound, and a 80 metal of the iron group as a catalyst, and heating the mixture thus produced at a temperature of at least about 1000° C. in the presence of nitrogen.

9. The herein described process of manufacturing cyanides, which comprises treating matter containing humic substances with water by heating under pressure, dissolving the formed free humic acid by adding a basic alkali compound, separating 90 from the solution the solid matter, thickening the solution by evaporation, heating the product in the presence of an alkali metal compound to produce coke therefrom, and heating the coke thus produced at a temperature of at least about 1000° C. in the presence of nitrogen.

10. The process of forming cyanogen compounds by causing nitrogen to react with a charge comprising a basic compound 100 of a metal selected from the alkali and alkaline earth metals and carbon produced by the carbonization of a humate.

11. The process of forming cyanogen compounds by causing nitrogen to react 105 with a charge comprising an oxidic compound of metal selected from the alkali and alkaline earth metals and carbon produced by the carbonization of a humate of such a metal.

12. The process of forming cyanogen compounds by causing nitrogen to react with a charge comprising a basic compound of an alkali metal and carbon produced by the carbonization of a humate.

In testimony whereof I hereunto affix my signature.

HERMANN WIEDERHOLD.
